UNITED STATES PATENT OFFICE.

AUGUST C. RADER, OF UPPER MONTCLAIR, NEW JERSEY.

CURTAIN-FIXTURE.

1,063,830.

Specification of Letters Patent.

Patented June 3, 1913.

Application filed May 18, 1912. Serial No. 698,265.

To all whom it may concern:

Be it known that I, AUGUST C. RADER, a citizen of the United States, residing at Upper Montclair, in the county of Essex and State of New Jersey, have invented a new and useful Curtain-Fixture, of which the following is a specification.

This invention relates to an improvement in holding devices for spring-actuated shades.

The primary object of the invention is to provide a holding device which will normally maintain the shade against movement, with means whereby the shade may be raised and lowered, by movement of the rod which is attached to its free edge.

A further object of the invention is to provide a construction in which the shoes which engage the window casing, may be released from frictional contact with the casing by a movement of the rod, there being a connection between the rod and shoes whereby the rod may be maintained at right angles to the casing during the raising and lowering of the shade.

A further object of the invention is to provide a construction in which pressure, applied to the rod in either direction, and at any point throughout its length will operate to bring the friction shoes out of contact with the casing.

A still further object of the invention is to provide a supporting member for the shoes, which is adjustable with respect to the rod and which houses resilient means for maintaining the shoes in contact with the window casing.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

Figure 1 is a view in elevation showing the shoes in their normal position to maintain the shade against movement. Fig. 2 is a view showing the shoes in the position they assume when downward pressure is exerted upon the rod. Fig. 3 is a view showing the position that the shoes assume when upward pressure is applied to the

rod. Fig. 4 is an enlarged sectional view, showing the connection between the shoes and the rod. Fig. 5 is a front elevation of the shoe. Fig. 6 is a view showing a slightly modified form of connection, between the adjustable member and shoe.

In the drawings 10 designates a hollow rod, which is attached to the edge of the shade. This rod is interiorly screw threaded adjacent its terminals, to receive the screw threaded barrel 11 which forms an adjustable support or connection, for the shoe. The end 12 of this cylindrical member 11, is closed by the screw threaded cap 70 or plug 14, said plug forming a contact block for a coiled spring 15. A rod or plunger 16 is disposed for sliding movement within the hollow member 11, said rod being provided with an elongated slot 17 which receives the pin 18, the pin 18 extending transversely of the cylindrical member 11, being positioned adjacent its end 19. The rod or plunger 16 terminates in the reduced rounded extension 20 which forms the male member of a knuckle joint. The shoe 21 consists of the spaced plates 22 and 24, rollers 25 and 26 being rotatably supported between the terminals of said plates. The plates are connected by the web portion 27 the surface 28 of which carries a strip 30 preferably formed of rubber and positioned between the plates 22 and 24. This strip of rubber extends beyond the edges 29 of the plates 22 and 24, the contact points 30 of said strip being substantially in alignment with the peripheries of the rollers 25 and 26. The plates 22 and 24 are provided with the spaced ears 31 and 32, said ears extending from the edges of said plates remote from the casing engaging side of the plates, this edge of the plate being curved, the edge which is presented to the casing being straight. The web 27 is provided with the extension 33 which is disposed centrally between the ears, said member 33 while preferably formed integral with the web, may be formed separately and secured either to the web or to the ears.

The terminal 34 of the extension is concaved as at 35 to form the female member of a knuckle joint. A pivot pin 36 passes through the ears, and pierces the outer terminal of the shaft or plunger 16, the said pin passing through the rounded extension 20 of said plunger, the extension 20 and the concaved terminal of the extension 34 form-

ing, a knuckle joint. The plunger 16 intermediate of the slot 17 and the terminal 20 is bored transversely to receive the bolt 37. A flat spring 38 is secured to the upper and 5 lower faces of the plunger 16, by said bolt the head 39 of said bolt retaining one of said springs in position and the nut 40 retaining the other of said springs in position. These springs are bowed at 41 and their terminals 42 contact with the extension 34 retaining said extension in alignment with the plunger 16, the plunger 16 thus normally being disposed at right angles with respect to the shoe, the outer terminal of the plunger 15 being formed square, to form a flat bearing surface for the portion 44 of the spring. It will be noted by this construction that the shoe has a pivotal connection with the plunger 16 and the plunger 16 has a sliding connection with the barrel which is attached to the rod 10, the coiled spring 15 maintaining the shoe in contact with the casing and the flat spring 41 holding the shoe at right angles to the rod 10. By this construction 20 it will be noted that the normal tendency of the spring 15 is to hold the shoe in contact with the window casing; the normal position of the retaining member being illustrated in Fig. 1. By referring to this figure it will be noted that the contact block 30 is 25 in engagement with the window casing 45, the frictional contact of said block with the casing overcoming any tendency of the shade spring to raise the shade. When it is desired 30 to lower the shade, the rod 10 is drawn downward (attention being called to Fig. 2 of the drawings) this downward movement of the rod exerting a downward pressure on the shoe at the pivot point 36'. It will be 35 noted that the shoe is pivoted eccentrically, the downward pressure on the rod causing the same to fulcrum on the lower roller 26. It will be noted that as the shoes are moved to a position where the rollers alone contact 40 with the casing that the shade may be conveniently lowered. When the shade has been 45 properly adjusted and the pressure is removed from the rod 10 the shoes will again assume the position shown in Fig. 1. When 50 it is desired to raise the shade, (attention being called to Fig. 3 of the drawings) upward pressure is exerted on the rod 10 causing the contact block 30 and the lower roller 26 to move out of contact with the casing 55 the rollers 25 forming the fulcrum on which the shoes pivot. It will be noted that when the shoes assume this position the shade may be raised, the shoes riding on the rollers 25 as the same is raised, it being noted that 60 when the shade is adjusted and the pressure on the rod 10 relieved, that the springs 41, will cause the shoe to assume a position at right angles to the rod 10 thus forcing the contact blocks 30 against the casing. In 65 this movement of the shoes which permits

the shade to be adjusted vertically the plunger 16 recedes within the barrel 11, the coiled spring 15 forcing said plunger outward as soon as the pressure on the rod 10 is relieved, the shoe thus being returned to its right angled position with respect to the rod and forced by the action of said springs 41 and 38 outward by the action of the spring 15. 70

It will be noted that by adjusting the shade the rod 10 may be maintained in a horizontal position there being no necessity of moving said rod out of its normal position at right angles to the casing for securing the proper adjustment of the shade. It will also be seen that the raising and lowering of the curtain may be secured by applying pressure to any point along the rod. Attention is called to the fact that the spring which normally maintains the shoes in contact with the casing, are actuated to allow the shade to be raised and lowered by applying pressure to the rod, in either direction and at any point throughout its length, the structure providing a spring actuated shade retaining means in which the adjustment of the shade is secured without the use of spring releasing triggers, it being unnecessary to bring the curtain rod out of its normal horizontal position to actuate the spring releasing means. This is of particular advantage inasmuch as the holding of said rod out of its normally horizontal position tends to damage the curtain. Furthermore it will be seen that the springs are released without the use of triggers or similar mechanism, and that the lower edge 46 of the curtain is unbroken, the rod 10, being slipped in the lower folded edge of the curtain. This is an advantage in assembling the device and placing the same on the curtain, the construction being such as may be easily and economically manufactured. 90 95 100 105

In the modified form shown in Fig. 6 the shoe 48 consists of the body portion 49 which supports the contact block 50 which is preferably formed of rubber. A plurality of curved roller supporting arms 51 are formed integral and attached to the body portion 49, the rollers 52 and 53 being disposed with respect to the contact pads 50 in the same manner that the rollers 25 and 26 are disposed with relation to the contact pads 30 in the preferred form. In this form the plunger 16' is disposed within the barrel 11', its terminal 17 being bifurcated and embracing the portion 54 of the shoe, the pivot pin 52 passing through the portion 54 of the shoe and the bifurcation of the plunger 16', the plunger 16' therefore having a pivotal connection with the shoe. The plunger 16' is provided with an elongated slot 17' which permits the plunger to slide within the barrel 11', a coiled spring 15' contacting with the transversely disposed 110 115 120 125 130

pin 18' which passes through the elongated slot 15', the outer terminal of said spring bearing against the portion 55 of the shoe, maintaining the body portion of the shoe in alinement with the barrel 11' in the same manner that the ears 31 and 32 are maintained in alinement with the barrel 11 in the preferred form. In this form when upward pressure is applied to the rod, the same action takes place as in the preferred form, the spring 15' performing the functions of both the spring 15 and the spring 38, the same having a tendency to extend the plunger 16' and through its contact with the surface 55 of the shoe maintaining the shoe at right angles to the rod.

The many advantages of this construction may be clearly apparent as it will be noted that the same may be easily and economically manufactured and that the various parts may be readily assembled.

What is claimed is:

1. A holding fixture for spring actuated shades, including a rod, casing engaging shoes, members connecting said shoes and said rod, said members being movable longitudinally of the rod, said shoes having a pivotal connection with said members, and spring means carried by each member for normally engaging a shoe at opposite sides of its pivot to maintain the shoe at right angles to its member.

2. A holding fixture for spring actuated shades, including a rod, casing engaging shoes, members connecting said shoes and said rod, said members being movable longitudinally of the rod, said shoes having a pivotal connection with said members, and a plurality of springs secured to said mem-

bers and contacting with said shoes to normally maintain the same at right angles to the members.

3. A holding fixture for spring actuated shades, including a hollow rod, the terminals of said rod being interiorly screw threaded, a screw threaded barrel disposed within each of the terminals of said rod, a plunger disposed for movement within said barrel, a plug forming a closure for one end of said barrel, a coiled spring interposed between said plug and the inner terminal of said plunger, a shoe, said shoe being formed with spaced ears, a pivot pin passing through said ears at their outer edges, said pin passing through the outer terminal of said plunger, an extension carried by the shoe, and springs carried by said plunger, said springs contacting with the extension of the shoe to maintain the shoe at right angles to the said plunger.

4. A holding fixture for spring actuated shades including a hollow rod, a barrel adjustably arranged within either end of said rod, a plunger mounted for a restricted sliding movement within said barrel, resilient means for normally maintaining said plunger at the limit of its outward movement, a shoe pivotally connected to said plunger, and a resilient connection between said plunger and said shoe, whereby the shoe is normally maintained at right angles to the plunger.

In testimony that I claim the foregoing as my own, I have hereto affixed my signature in the presence of two witnesses.

AUGUST C. RADER.
